CLAIM

The ornamental design for a counter display stand, as shown and described.

DESCRIPTION

FIG. 1 is a top plan view of the counter display stand showing my new design;

FIG. 2 is a front elevational view of FIG. 1;

FIG. 3 is a rear elevational view of FIG. 1;

FIG. 4 is a bottom plan view of FIG. 1;

FIG. 5 is a side elevational view taken from the right of FIG. 2;

FIG. 6 is a perspective view of a second embodiment of the design of FIG. 1; the only differences residing in the off-center orientation of the shelves and the omission of the base.
